CLOTH CUTTING MACHINE

Evelyn L. Nesbitt, Yucaipa, Calif.

Application July 12, 1954, Serial No. 31,398

Term of patent 7 years

(Cl. D22—3)

FIG' 1

FIG' 2

FIG' 3

FIG' 4

FIG' 5

Fig. 1 is a top plan view of a cloth cutting machine, showing my new design;

Fig. 2 is a side elevational view thereof;

Fig. 3 is a front elevational view;

Fig. 4 is a rear elevational view; and

Fig. 5 is an elevational view thereof showing the side opposite to that of Fig. 2.

I claim:

The ornamental design for a cloth cutting machine, substantially as shown.
